(57) **CLAIM**

The ornamental design for a baseball cap and player head cooler-carrier, as shown and described.

DESCRIPTION

FIG. 1 is a front elevational view of a baseball cap and player head cooler-carrier showing my new design; wherein the phantom lines form no part of the design;

FIG. 2 is a left side elevational view thereof; the opposite side being a mirror image;

FIG. 3 is a right side view with handle collapsed and cooler cap open; wherein the phantom lines form no part of the design;

FIG. 4 is a back view of FIG. 3;

FIG. 5 is a top view of FIG. 3; wherein the phantom lines form no part of the design; and,

FIG. 6 is a perspective left side view with cap-cooler open and handle raised; wherein the phantom lines form no part of the design.
